UNITED STATES PATENT OFFICE.

ALEXANDER DOM, OF MOUNT HEALTHY, OHIO.

BOOK-HOLDER.

SPECIFICATION forming part of Letters Patent No. 359,245, dated March 15, 1887.

Application filed February 6, 1883. Serial No. 84,138. (Model.)

To all whom it may concern:

Be it known that I, ALEXANDER DOM, a resident of Mount Healthy, in the county of Hamilton and State of Ohio, have invented 5 certain new and useful Improvements in Book-Holders, of which the following is a specification.

My invention relates to holders for supporting a single large book, such as dictionaries 10 and the like.

The object of one of the principal features of my invention is to provide a holder which will cause the opposite pages of the book to be always on the same level, or nearly so, when 15 the book is opened, no matter where it may be opened.

The various features of my invention and the advantages resulting from their combined use, and also from their use singly or in groups 20 of two or more, and in connection where applicable to book-holders of construction different from that herein shown, will be apparent from the following specification.

For the purpose of more fully illustrating 25 my invention, I have shown it applied to a book.

Referring to the drawings forming part of this specification, Figure 1 is a perspective view of my invention, the book being closed. 30 Fig. 2 is a perspective view of the same, the book being open. Fig. 3 represents one form 35 of base for the holder, with portions of the holder in section. Fig. 4 is a vertical transverse section taken at a point indicated by the dotted line xx in Fig. 1. Fig. 5 is an enlarged view of a detached portion. Fig. 6 is a perspective view showing a clasp and handle. Figs. 7 and 8 represent modifications of one 40 portion of my invention. Fig. 9 is an isometric view showing modes of applying certain features of my invention to a table or desk. Fig. 10 is an elevation showing another mode 45 of applying certain features of my invention to a table or desk. Fig. 11 shows another form of device for enabling the book to be inclined and set at a desired inclination.

The holder proper may be supported in any desired manner, and the base A may be of any desired form. When not supported by a table or desk, a preferred means for upholding it 50 consists of a base having a perpendicular

opening to receive the lever portion of standard A' and allow the latter to turn therein. For the purpose of adjusting the height of the book so as to adapt it to be more conveniently used at will by adult persons or children and by persons sitting or standing, I employ as a preferred means a set-screw, a , which works in the usual manner in the base and against the standard A', and by this set-screw a the standard A', after being raised or lowered, as desired, is secured at the selected elevation. To the top portion of the standard A' is secured a neck, B, being preferably so secured as to be capable of turning freely in either direction, the preferable means being that shown, and which are as follows: A cup or sleeve, a' , is formed in the lower end of the neck B, a set-screw, a' , passing through the cup or sleeve a' and into a groove around the end of the standard A', permitting the cup a' to turn freely, but preventing it from being lifted from the standard.

It is convenient in practice to use the book when the plane of its open or reading surface 75 makes an angle with a horizontal plane—that is to say, when the edge of the open book which is next to the person inspecting its contents is lower than the opposite edge—and it is also desirable to regulate the degree of such inclination. A preferred means for enabling such adjustment to be carried into effect is as follows: To the upper end of neck B is connected a supporting-yoke, R, consisting of horizontal piece r and uprights S , so pivoted or hinged 80 that it may be caused to assume different angles with the standard. A quadrant-rod, b , is secured at one end to the yoke R, the other end passing through the neck B, in which it may be secured at any desired point by a set-screw, b' , by which means the yoke R may be 85 set at any desired angle.

To the upper ends of uprights S of yoke R are pivoted one end of the swing-rods C, the other ends of said rods being connected to the 95 ends of the side pieces or frames, D, made solid or open, as desired, forming the top of the holder at or near the lower edges of said pieces D. When the book is not secured to the side pieces or frames, D, in such a manner 100 that it will not slip down when closed, a flexible strip or strips, d , are connected to the side

pieces or frames, D, at or near their lower edges. This strip will hold the book in position between the side pieces when closed. These side pieces, D, and also the strip d', when present, form the top of the holder and support for the book, the sides of the cover of which are secured to the side pieces, D, by suitable means, preferably by clamping-strips d', made of metal, one end of said strips being secured to the side pieces, D, of the holder, the other ends being bent down around the edges of the cover of the book, holding the cover firmly in contact with the side pieces, D, of the holder. The side pieces, D, may be so connected to the book as to prevent the latter from slipping down between them when the book is closed, and in such event the strip or strips d' may be dispensed with. For instance, the clamping-strip d' may be provided with a point or tooth, and when the said strip is bent around the edge of the cover this point may be driven firmly into the cover of the book.

When the book is closed, the side pieces, D, fold up, as shown in Fig. 1, and when the book is open the side pieces, D, assume a horizontal position, as shown in Fig. 2. Any other suitable means for securing the book to the side pieces may be employed, and these means may be such as contemplate one book only being constantly used with said holder, or which admit of the book in the holder being removed and another book being substituted therefore as often as desired.

To the horizontal bar r, near its longitudinal center, is secured a plate, E, extending at right angles to the length of the yoke, and in this plate is a slot, e, and in this slot are two studs or buttons, e', to each of which is connected one end of a rod, E', the other end of each of which rods is connected to that side piece, D, to which it is adjacent, preferably by a hinge-connection, as shown in Figs. 1 and 4, the upper end of each of the rods E' being formed into an eye which engages with a plate, e'', secured to the side piece, D. The studs e' are capable of being moved from one end of the slot e to the other.

When the book is secured to the side pieces, D, of the stand, it is supported, as it were, in a swing by the swing-rods C, which are connected to the uprights S, which swing is capable of a slight amount of lateral motion, the extent of which is governed by the length of the slot e in the plate E.

When the book is opened, it and the side pieces, D, of the holder assume the position shown in Fig. 2. If the book be opened in the middle, there will be an equal weight on each of the side pieces, D, and the studs e' will remain in the middle of the slot e; and when it is opened at either side of the middle there will be more weight on one side piece, D, than on the other, and this additional weight bearing down on the rod E', connected to the side piece, D, on which the additional weight is placed, carries the studs e' to the opposite end of the slot e, which causes the rod E', con-

nected to the side piece, D, bearing the lighter weight, to lift this side piece. Thus it will be seen that as one side of the book becomes heavier than the other it is depressed, and the opposite or lighter side is elevated to an equal degree, keeping the pages undergoing inspection at all times elevated to the same level at both sides, as illustrated by Fig. 2.

It is evident that that lateral movement allowed to the rods E', which in the aforesaid illustration is afforded by the slot e, permits the book to be opened and closed.

In the modification shown in Fig. 8 the lateral movement necessary to the rods E' is afforded at the sides of the side pieces as follows: The plate e'', affixed to the side piece, D, is provided with a flange or projection, e'', containing a slot, e'. The end of the rod E' is provided with a projection, f, which plays in said slot, said projection being prevented from slipping out of the flange by means of a nut, stud, or enlargement, f'. Suitable stops, h h, are affixed, as shown, to the rods E', which are now pivoted together at g, as shown, and in connection with the horizontal bar r, act as stops for the rods E' in the same manner as the ends of slot E did in the former instances. When the plates e'' are thus slotted, suitable means are employed for supporting the rods E'—for example, a swinging yoke, B'', (see Figs. 7 and 8,) pivoted to the uprights S, where the rods C are pivoted, and connected to the rods E' at their pivotal point of connection, may be employed.

It is now apparent from the described operation of the rods C, their supporting-yoke R, the movement of the book in connection with said rods C and rods E', and the provision for their necessary play, that the side pieces or frames, D, might be dispensed with, and the lower ends of the rods C connected directly to the edges of the book-cover by suitable means, and the plates might also be connected to the surface of said cover at substantially the same point where they are now connected to the side pieces. All such modifications will come within the scope of my invention.

When my invention is constructed and applied substantially as described, it will operate; when the book has been shut, to keep the book tightly closed until opened by human agency, and when opened the book will remain open until closed by human agency.

When it is desired to employ any additional means for keeping the book, when not in use, tightly closed, any suitable clamp may be employed. A preferred form of such clamp, which may also be employed for lifting the holder and book, is shown in Figs. 4 and 6, and is as follows: To the upper edge of each of the side pieces, D, is connected a metal loop, I, the connection being made by the plates or ears J, the ends of the loops being formed into eyes and passing through said ears, as shown. One of the loops I is bent, as shown, to form a hook, j, which hooks into the opposite loop, and when so arranged these loops form a clasp

to hold the book closed, and also serve as a handle by which the stand and book may be lifted and carried about. In order to prevent too great a jar when the standard A' is lowered, by reason of the sleeve a' dropping on the upper end or portion of the base A of the holder, I employ a bumper, K, either in the form of a spiral spring, as shown, or other elastic substance, upon which the sleeve a' strikes when the standard is lowered.

It may sometimes be desired to support the book upon a table or desk, instead of on a movable stand, as above described, in which event the table or desk will form the base A, and the standard A' and neck B may be dispensed with and the yoke R attached directly to the table or desk, (see left-hand holder, Fig. 9,) or the yoke may be dispensed with and the swing-rod C be connected to the top of uprights or posts S, secured to the desk, (see right-hand holder, Fig. 9,) the plate E being also secured to the desk in a position corresponding to that which it occupies on the yoke R.

The operation and the remaining features of my invention are similar in all respects to that already described.

In the modification shown in Fig. 10 the uprights S are fixed to a platform, M, capable of being rotated upon the wheels m. When preferred, the uprights S may be suitably supported upon single vertical rods set into the table, or a suitable step, and turning therein.

The device may be arranged so as to always remain open at some one point or another.

Various descriptions of devices for clamping or setting the holder so that the open surface of the book may be set in a horizontal plane, or an angle thereto, as aforementioned, may be employed instead of the quadrant b and set-screw shown. A very simple and convenient form of a setting device for this purpose is shown in Fig. 11, and consists in connecting a suitable portion of base A to a disk or piece, N, and the neck B to another disk or piece, N', of similar size. These disks are held in contact by a set-screw, preferably a thumb-screw, n, whose shank preferably passes through one disk and preferably engages a screw-thread in the other, but may pass through the latter and engage a nut on the outer side of the latter. Turning the thumb-screw in one direction brings the disks forcibly together and sets the holder at the angle at which it has been placed; and reversing the direction in which the thumb-screw is turned loosens the hold of the disks upon one another. In order that the disks may be more securely prevented from slipping when screwed or otherwise brought together, and that the force required to hold them in position may be economized, their inner or meeting faces are preferably roughened, indented, or corrugated.

The pieces N need not be disks, but may be angular or other desired configuration.

What I claim as new and of my invention, and desire to secure by Letters Patent, is—

1. The combination of side pieces, D, flexible strip d, uprights S, pairs of pivoted swing- rods C, hinge-rods E', and slotted stop, substantially as and for the purposes specified. 70

2. The combination of pieces D, flexible strip d, yoke R, pairs of pivoted swing-rods C, hinge-rods E', and means, substantially as described, whereby a limited amount of movement of rods E' is permitted, substantially as and for the purposes specified. 75

3. In a book-holder, the combination of rods C, pivoted at their upper and lower ends, substantially as described, uprights S, pivoted to rods C, hinge-rods E', and stops for limiting their oscillation, substantially as and for the purposes specified. 80

4. In a book-holder, the combination of pieces D, uprights S, rods C, pivoted together 85 and to uprights S, substantially as described, hinged rods E', and stop, substantially as and for the purposes specified.

5. In a book-holder, the combination of pieces D, swinging-rods C, uprights S, swing- 90 rods E', and stationary slotted piece E, substantially as and for the purposes specified.

6. The combination of a swinging support, as rods C, uprights S, and the rods E', the side pieces, D, connected to the rods C, and 95 mechanism, substantially as specified, connected to rods E', for allowing them to conjointly move to allow the heaviest side or portion of the open book to be depressed and the lighter portion to be elevated, substantially as 100 and for the purposes specified.

7. In a book-holder, the combination of plates e², rods E', swing-rods C C, uprights S, the studs e', rods E', and slotted plate E, substantially as and for the purposes set forth. 105

8. In a book-holder, the combination of plates e², pieces D, rods E', swinging rods C, uprights S, and plate E, provided with a slot in which the ends of rods E', disconnected from each other, play, substantially as and for the 110 purposes specified.

9. In a book-holder, the combination of the side pieces, D, flexible strips d, swing-rods C, rods E', slotted plate E, and uprights S, substantially as and for the purposes specified. 115

10. In a book-holder, the combination of the side pieces, D, clamps d', flexible strips d, rods C, rods E', and the uprights S and the slotted plate E, for allowing the heavier side 120 of the book when open to sink and the lighter portion to be elevated till the open faces of the book are on a level, substantially as and for the purposes specified.

11. In a book-holder, in combination with 125 the side pieces, D, connected at rear, the clamps j, substantially as and for the purposes specified.

12. The combination of a book-holder supporting-standard, neck B, bar r, and quadrant b, 130 the standard being located under the center of the holder and terminating in neck B, the neck B being pivotally connected to rod r at one side of center and engaging a quadrant, as b,

connected to the bar *r* at the other side of the center, substantially as and for the purposes specified.

13. The combination of the base *A*, provided with a perpendicular hole, standard *A'*, engaging base *A* and provided with sleeve or shoulder *a'*, and spring *K*, substantially as and for the purposes set forth.

14. The combination of side pieces, *D*, uprights *S*, pairs of pivoted swing-rods *C*, hinged rods *E'*, and slotted plate *E*, substantially as and for the purposes specified.

15. In a book-holder, the combination of the uprights *S*, pivoted links *C*, sides *D*, and hinged rods *E'*, and slotted piece for allowing the rods *E'* to travel in a reciprocating path, and means for limiting the swing or oscillation of the rods *E'*, substantially as and for the purposes specified. 15
